UNITED STATES PATENT OFFICE.

GEORGE P. McARTHUR, OF ROCKLEDGE, PENNSYLVANIA.

PIPE-BENDING MECHANISM.

1,353,168.

Specification of Letters Patent. Patented Sept. 21, 1920.

Application filed November 2, 1918. Serial No. 260,774.

To all whom it may concern:

Be it known that I, GEORGE P. McARTHUR, a citizen of the United States, residing at Rockledge, in the county of Montgomery 5 and State of Pennsylvania, have invented a certain new and useful Improvement in Pipe-Bending Mechanism, whereof the following is a specification, reference being had to the accompanying drawings.

10 My invention was designed to bend copper elbows and the primary object and effect thereof is to enable unskilled manual laborers to produce a product heretofore requiring the labor of skilled copper smiths. 15 However, I do not desire to limit myself to such use of my invention.

As hereinafter described, my mechanism includes two die elements, between which the pipe is engaged and bent, by relative 20 movement of said elements. One of said elements, which I term a die frame, is a casting having a cylindrical curved face, with a toric die channel extending circumferentially in said face, a quadrant of a circle, 25 and adapted to receive substantially one-half of the diameter of the pipe to be bent. I provide means at one end of said channel to rigidly clamp the end of the pipe which is to be bent; so that said pipe will bend 30 into said channel when traversed by the other die element, which is a roller having a toric channel in its circumference complementary to the toric channel in said die frame. Said roller is caused to traverse the 35 pipe, in concentric relation with the die channel in said frame, by a lever which is fulcrumed in coaxial relation with said cylindrically curved die face and of such length that the bending operation may be 40 rapidly effected manually by a single unskilled operator walking in a path concentric with said fulcrum and pushing said lever before him.

My invention includes the various novel 45 features of construction and arrangement hereinafter more definitely specified. For instance, although, as exemplified by one form of my invention hereinafter described, the die frame may be made in integral relation with a base which is provided with the fulcrum for the lever; such a form necessitates the construction of a base for each pattern of die frame. Therefore, I find it convenient to provide a single base with a single 55 lever, and a plurality of die frames of dif-

ferent patterns which may be interchangeably secured upon the base, and a plurality of complementary die rollers which may be interchangeably mounted upon the lever, and also to provide clamping mechanism in 60 which shoes respectively conforming to different sizes of pipe, may be interchangeably fitted, as hereinafter described.

In the drawings; Figure I is a plan view of a bending mechanism embodying my invention, wherein die frames of different sizes may be interchangeably employed. 65

Fig. II is a fragmentary, vertical sectional view of said mechanism, taken on the line II in Fig. I. 70

Fig. III is a plan view of a bending mechanism embodying my invention, wherein the die frame is in integral relation with the base.

Fig. IV is a fragmentary vertical sectional view of the mechanism shown in Fig. III, taken on the line IV in Fig. III. 75

Fig. V is a radial sectional view of a die frame and a die roller of a smaller size than those shown in Figs. I and II, but adapted 80 to be interchangeably mounted on the base and lever shown in said Figs. I and II.

Fig. VI is a vertical sectional view of a clamping shoe, corresponding in size with the die elements shown in Fig. V, and adapted 85 to interchangeably fit the clamping yoke shown in Figs. I and II.

Fig. VII is an outside elevation of the yoke and clamping shoe, shown in Figs. I and II, attached to the die frame. Fig. VIII 90 is an inner end elevation thereof.

Referring to the form of my invention shown in Figs. I and II; the base 1, which may be conveniently formed of cast metal, is provided with an arcual series of independently adjustable pedestals 2, which may be secured on said base, by bolts 3 engaging bolt holes 4, so as to form arcual series of different curvatures, in accordance with the sizes of the die frames which they are 95 adapted to interchangeably support on said base. The die frame 7 is detachably mounted on said pedestals, conveniently held by bolts 8, and has the cylindrically curved face 9 with its axis, at the point 10, 105 extending vertically and normally with respect to said base, and with the toric die channel 12 extending circumferentially in said face, adapted to receive substantially one-half of the diameter of the pipe to be 110

bent. The yoke lugs 14 on said frame 7, at respectively opposite edges of said channel 12, near one end thereof, are adapted for detachable connection, by the bolts 15, 5 with a pipe clamping device, including the yoke 16 extending substantially radially with respect to said axis. Said yoke conveniently includes a pair of U-shaped wrought metal plates having perforated ends 10 17 respectively fitted to said frame lugs 14. The filling blocks 18 are rigidly secured between said plates, in the respective limbs of said yoke 16, and each has a rib 20 extending radially with respect to said axis, 15 inwardly with respect to said yoke, and in parallel relation. However, it is to be understood that said yoke and ribs may be cast in unitary relation. In either case; said yoke 16 may have its ends secured to 20 the yoke lugs, upon either side of the latter; that is to say; either on the outer side, nearest the outer end of said channel 12, as shown in Figs. I and III, or on the inner side of said lugs, toward the middle of the 25 length of said channel; the yoke being thus adjustable circumferentially upon the die frame 7 in accordance with different sizes of die rollers employed, as hereinafter described; it being desirable, in some instances, 30 to clamp the pipe to be bent, as closely to the roller as possible. The clamping shoe 21 is fitted to slide in said yoke 16, radially with respect to said axis, and has the grooves 22 fitted to said ribs 20; the toric channel 35 24 complementary to said channel in said die frame 7; and the screw threaded socket 25 extending radially in said shoe toward the bight in said yoke 16. The cap screw 26 is adjustably fitted in said socket 25 and the set screw 27, in said shoe, is arranged to 40 hold said cap screw 26 in adjusted position. The clamping lever 29 has the eccentric head 30 extending between said plates of the yoke 16, in opposition to said cap screw 26, and 45 is fulcrumed on the bolt 31 extending through said plates and lever.

I find it convenient to provide the springs 33 and 34, connecting said yoke 16 and shoe 21, respectively above and below the center 50 of said shoe, the lower spring 34, having its end connected to said yoke above the level of its connection with said shoe, whereby said spring counter-balances part of the weight of said shoe, and both springs tend 55 to withdraw said shoe 21 from said die frame 7, in opposition to said lever head 30.

In the form of my invention shown in Figs. I and II; I find it convenient to secure the primarily separate standard 36, 60 upon said base 1, by the bolts 37, as a support for the fulcrum bolt 39, in coaxial relation with said die face 9, as the fulcrum for the bending lever 40, which, as shown in Fig. II, is bifurcated and has only the upper 65 one of its bifurcations fulcrumed on said

bolt 39. Said lever has oppositely alined pintle slots 42 and 43, respectively in its upper and lower bifurcations, the axes of said slots being parallel with said frame axis, and the upper slot being wider than 70 the lower slot. Said lever 40 also has the radial screw threaded socket 45 in its bight. The pintle 46 extends in said slots 42 and 43, with its axis parallel with the axis of said frame; the lower end of said pintle 75 being of reduced diameter to fit the narrower slot 43; such construction and arrangement being merely to support the pintle in operative position and permit it to be readily manually removed by merely 80 lifting it, to insert or remove the die roller 48 which is mounted to rotate on said pintle 46 and has the toric channel 49 in its circumference, complementary to said toric channel 12 in said die 85 frame 7. The U-shaped roller housing 50 is fitted to slide between the bifurcations of said lever 40, parallel therewith, and has perforations 51 in its limbs to receive said pintle 46; said limbs being respectively interposed between said roller and the bifurcations of said bending lever 40. Said roller housing 50 has the cylindrical plunger bearing 52 extending radially in its bight as a journal for the inner end of the rotary housing plunger 53 which has the screw thread 54 fitted in said screw socket 45 of said lever 40. Said plunger is preferably provided with the wrench hold 56 at its outer end, whereby it may be conveniently rotated, 90 and has the nut 57 on its reduced and screw threaded inner end 58. A pin 59, or other suitable means, may be provided to prevent accidental displacement of said nut. It is to be understood that said roller 48 may 105 be adjusted toward and away from said die face 9 by rotation of said plunger 53 in said bending lever 40, so as to coöperatively embrace the pipe 60 between said die elements 7 and 48, in such relation as to 110 permit said roller 48 to traverse said curved face 9 when said lever is turned upon its fulcrum 39 aforesaid.

In order that the leverage to which the die roller is subjected may be varied in accordance with the work to be performed, which varies within wide limits, in accordance with the diameter and thickness of the pipe which is to be bent; I find it convenient to supplement the short lever 40 above described, with a tubular extension 61, which may be a piece of standard wrought iron pipe, which is merely slipped over said plunger 53 so that it may be instantly removed to permit adjustment of the latter.

In the form of my invention shown in Figs. III and IV; the base 63 is in unitary relation with the die frame 64 and with the standard 65 which supports the fulcrum bolt 67, upon which the bending lever 68 is ful- 130

crummed. Otherwise, the construction, arrangement, and method of operation thereof, are as above described.

Referring to Fig. V; the die frame 71 is similar to the die frame 7 above described, but has a toric die channel 72 for smaller size pipe 73, in its face 74 which is an arc of a smaller circle than said face 9. The die roller 75 which is complementary to said die frame 71, is similar to the die roller 48, above described, but has a smaller sized toric die channel 76.

Referring to Fig. VI; the clamping shoe 78 is similar to the clamping shoe 21 above described, but is of smaller size, in correspondence with the die elements 71 and 75, with which it is designed to coöperate.

The mechanism shown in Figs. I, II, and VII may be conveniently operated as follows: The cap screw 26 is adjustably fitted in said socket 25 so that when the clamping lever 29 is upturned to vertical position, said shoe 21 is retracted by the springs 33 and 34 to permit a straight, cut length, of pipe 60 to be freely inserted between the die frame 7 and the roller 48 which is brought up against the yoke 16, by the lever 40, for that purpose. Said clamping lever 29 is then turned down to horizontal position; the eccentricity of its head 30 being such as to properly clamp said pipe 60 by movement of said lever to that extent. Thereupon, the operator pushes the bending lever 40, by its tubular extension 61, so as to cause the die roller 48 to traverse said pipe 60, in concentric relation with the axis of the die frame 7, to the extent necessary to bend the pipe 60 to the desired degree. It is to be understood that, although the die frame 7 is designed to permit a pipe to be bent in its channel 12 to the extent of one-quarter of a circle; bends of less arcual extent may be made by correspondingly less movement of the bending lever.

When it is desired to substitute the smaller die frame 71 and its coöoperative elements, for those shown upon the base 1 in Figs. I and II; it is merely necessary to remove the bolts connecting the pedestals 2 with the base 1 and die frame 7; secure the pedestals in the desired new arcual relation upon said base, with the die frame 71 thereon; remove the pintle 46 and die roller 48, substitute the die roller 75, replace said pintle in engagement therewith, substitute the clamping shoe 78 for the clamping shoe 21; and adjust the housing plunger 53, if necessary.

Therefore, I do not desire to limit myself to the precise details of construction and arrangement herein set forth, as it is obvious that various modifications may be made therein without departing from the essential features of my invention as defined in the appended claims.

I claim:

1. In a pipe bending mechanism, the combination with a base; of an arcual series of independently adjustable pedestals on said base; a die frame detachably mounted on said pedestals, and having a cylindrically curved face, with its axis extending vertically with respect to said base and with a toric die channel extending circumferentially in said face, adapted to receive substantially one-half of the diameter of the pipe to be bent; yoke lugs on said frame, at respectively opposite edges of said channel, near one end thereof; a pipe clamping device, including a yoke extending substantially radially with respect to said axis, including a pair of U-shaped plates having perforated ends respectively fitted to said frame lugs, and filling blocks between said plates, in the respective limbs of said yoke; each of said blocks having a rib extending radially with respect to said axis; said ribs extending inwardly with respect to said yoke, and in parallel relation; a clamping shoe fitted to slide in said yoke, radially with respect to said axis, having grooves fitted to said ribs, a channel complementary to the channel in said frame, a screw threaded socket extending radially in said shoe toward the bight in said yoke, a cap screw adjustably fitted in said socket, and a set screw in said shoe arranged to hold said cap screw in adjusted position; a clamping lever having an eccentric head extending between said plates, in opposition to said cap screw; a fulcrum bolt extending through said plates and lever; springs connecting said yoke and shoe respectively above and below the center of said shoe, the lower one of said springs having its end connected to said yoke above the level of its connection with said shoe, whereby, said spring counterbalances part of the weight of said shoe, and both springs tend to withdraw said shoe from said die, in opposition to said lever head; a fulcrum bolt for a bending lever in said frame in coaxial relation with said die face; a bifurcated bending lever having one of its bifurcations fulcrumed on said bolt and having opposite pintle slots in its bifurcations with their axes parallel with said frame axis, the upper slot being wider than the lower slot, said lever having a radial screw threaded socket in its bight; a pintle extending in said slots with its axis parallel with the axis of said frame, the lower end of said pintle being of reduced diameter to fit the narrower slot; a die roller mounted to rotate on said pintle and having a toric channel in its circumference complementary to the toric channel in said die frame; a U-shaped roller housing fitted to slide between the bifurcations of said lever, parallel therewith, having perforations in its limbs to receive said pintle and having its limbs respectively interposed

between said roller and the bifurcations of said lever, and having a cylindrical plunger bearing extending radially in its bight; a housing plunger having a screw thread fitted 5 in the screw thread of said lever, having a wrench hold at its outer end, and having its inner end reduced and mounted to turn in the bearing in said housing bight; a nut on the reduced end of said plunger; and means 10 preventing accidental displacement of said nut; whereby said roller may be adjusted toward and away from said die face, by rotation of said plunger in said bending lever; and a tubular handle, detachably fitted over 15 said plunger; whereby said roller may be caused to traverse said die face to bend a pipe held by said clamping shoe.

2. In a pipe bending mechanism, the combination with a base; of a die frame having 20 a cylindrically curved face, with its axis extending vertically with respect to said base and with a toric die channel extending circumferentially in said face, adapted to receive substantially one-half of the diameter 25 of the pipe to be bent; a pipe clamping device, including a U-shaped yoke extending substantially radially with respect to said axis, its limbs having respective ribs extending in parallel relation, and radially 30 to said axis; a clamping shoe fitted to slide in said yoke, on said ribs, having a channel complementary to the channel in said frame, and a screw threaded socket extending radially in said shoe toward the bight in said 35 yoke; a screw adjustably fitted in said socket; a clamping lever having an eccentric head extending in said yoke, in opposition to said screw; a fulcrum bolt extending through said yoke and lever; a spring connecting said yoke and shoe, tending to withdraw 40 said shoe from said die, in opposition to said lever head; a fulcrum on said base, in coaxial relation with said die face; a bifurcated bending lever on said fulcrum, having 45 opposite pintle slots in its bifurcations with their axes parallel with said frame axis, and a radial screw threaded socket in its bight; a pintle extending in said slots with its axis parallel with the axis of said 50 frame; a die roller mounted to rotate on said pintle and having a toric channel in its circumference complementary to the toric channel in said die frame; a roller housing fitted to slide in said lever, carrying said 55 pintle and having a cylindrical plunger bearing extending radially in its bight; a housing plunger having a screw thread fitted in the screw socket of said lever, and having its inner end mounted to turn in the bearing 60 in said housing bight; whereby said roller may be adjusted toward and away from said die face, by rotation of said plunger in said bending lever.

3. In a pipe bending mechanism, the combination with a base; of a die frame hav-

ing a cylindrically curved face, with its axis extending vertically with respect to said base and with a toric die channel extending circumferentially in said face, adapted to receive substantially one-half of the diameter of the pipe to be bent; a pipe clamping device, including a yoke; a clamping shoe fitted to slide in said yoke, radially with respect to said axis, having a channel complementary to the channel in said frame 70 and a screw threaded socket; a screw adjustably fitted in said socket; a clamping lever carried by said yoke, having an eccentric in opposition to said screw; a spring connecting said yoke and shoe tending to withdraw 80 said shoe from said die, in opposition to said lever; a fulcrum on said base, in coaxial relation with said die face; a bending lever on said fulcrum having a screw threaded socket radial to said axis; a pintle carried 85 by said bending lever with its axis parallel with the axis of said frame; a die roller mounted to rotate on said pintle and having a toric channel in its circumference complementary to the toric channel in said die 90 frame; a roller housing fitted to slide on said lever, having bearings for said pintle, and having a cylindrical plunger bearing; and a housing plunger having a screw thread fitted in the screw socket of said bending 95 lever, and having its inner end journaled in the bearing in said housing; whereby said roller may be adjusted toward and away from said die face, by rotation of said plunger in said bending lever.

4. In a pipe bending mechanism, the combination with a base; of a die frame having a curved face, with its axis extending vertically with respect to said base and with a die channel extending in said face, 105 adapted to receive part of the pipe to be bent; a pipe clamping device, including a clamping shoe fitted to slide radially with respect to said axis, having a channel complementary to the channel in said frame and 110 a screw threaded socket; a screw adjustably fitted in said socket; a clamping lever connected to said frame in opposition to said screw; a spring tending to withdraw said shoe from said die in opposition to said lever; a fulcrum on said base, in coaxial relation with said die face; a bending lever on said fulcrum, having a screw threaded socket radial to said axis; a pintle carried 115 by said bending lever with its axis parallel with the axis of said frame; a die roller mounted to rotate on said pintle and having a channel in its circumference complementary to the channel in said die frame; a roller housing fitted to slide on said lever, 120 having bearings for said pintle, and having a cylindrical plunger bearing; and a housing plunger having a screw thread fitted in the screw socket of said bending lever, 125 and having its inner end journaled in the 130

bearing in said housing; whereby said roller may be adjusted toward and away from said die face, by rotation of said plunger in said bending lever.

5. In a pipe bending mechanism, the combination with a base; of a die frame having a curved face, with its axis extending normally to said base and with a die channel extending in said face, adapted to receive 10 part of the pipe to be bent; a pipe clamping device, including a clamping shoe fitted to slide radially with respect to said axis, having a channel complementary to the channel in said frame; a clamping lever connected to said frame in opposition to said shoe; a spring tending to withdraw said shoe from said die, in opposition to said lever; a fulcrum on said base, in coaxial relation with said die face; a bending lever 15 on said fulcrum, having a screw threaded socket radial to said axis; a pintle carried by said bending lever with its axis parallel with the axis of said frame; a die roller mounted to rotate on said pintle and having 20 a channel in its circumference complementary to the channel in said die frame; a roller housing fitted to slide on said lever, having bearings for said pintle, and having 25 a cylindrical plunger bearing; and a housing plunger having a screw thread fitted in the screw socket of said bending lever, and having its inner end journaled in the bearing in said housing; whereby said roller may be 30 adjusted toward and away from said die face, by rotation of said plunger in said bending lever.

6. In a pipe bending mechanism, the combination with a die frame having a cylindrically curved face and a toric die channel 40 extending circumferentially in said face, adapted to receive substantially one-half of the diameter of the pipe to be bent; of a pipe clamping device, including a clamping shoe adjustable toward and away from said die frame, and having a channel complementary to the channel in said frame; a clamping lever arranged to shift said shoe toward 45 said frame; a spring tending to withdraw said shoe from said die in opposition to said lever; a fulcrum in coaxial relation with said die face; a bending lever on said fulcrum, having a screw threaded socket radial to said axis; a pintle carried by said bending lever with its axis parallel with the axis 50 of said frame; a die roller mounted to rotate on said pintle and having a channel in its circumference complementary to the channel in said frame; a roller housing fitted to slide on said lever, having bearings 55 for said pintle, and having a cylindrical plunger bearing; and a housing plunger having a screw thread fitted in the screw socket of said bending lever, and having its inner end journaled in the bearing in 60 said housing; whereby said roller may be adjusted toward and away from said die face, by rotation of said plunger in said bending lever.

justed toward and away from said die face, by rotation of said plunger in said bending lever.

7. In a pipe bending mechanism, the combination with a die frame having a cylindrically curved face and a toric die channel 70 extending circumferentially in said face, adapted to receive substantially one-half of the diameter of the pipe to be bent; of a pipe clamping device, including a clamp- 75 ing shoe adjustable toward and away from said die frame, and having a channel complementary to the channel in said frame; a clamping lever arranged to shift said shoe toward said frame; a fulcrum in coaxial re- 80 lation with said die face; a bending lever on said fulcrum, having a screw threaded socket radial to said axis; a pintle carried by said bending lever with its axis parallel with the axis of said frame; a die roller 85 mounted to rotate on said pintle and having a channel in its circumference complementary to the channel in said die frame; a roller housing fitted to slide on said lever, having 90 bearings for said pintle, and having a cylindrical plunger bearing; and a housing plunger having a screw thread fitted in the screw socket of said bending lever, and having its inner end journaled in the bearing in 95 said housing; whereby said roller may be adjusted toward and away from said die face, by rotation of said plunger in said bending lever.

8. In a pipe bending mechanism, the combination with a base; of an arcual series of 100 independently adjustable pedestals on said base; a die frame detachably mounted on said pedestals, and having a curved face, with its axis extending normally to said frame and with a die channel extending circumferentially in said face, adapted to receive 105 substantially one-half of the diameter of the pipe to be bent; a pipe clamping device, including a yoke extending substantially radially with respect to said frame; a clamping shoe, adjustable in said yoke, radially with respect to said axis, having a channel complementary to the channel in 110 said frame and a screw threaded socket; a screw adjustably fitted in said socket; a 115 clamping lever fulcrumed on said yoke, having an eccentric in opposition to said screw; springs connecting said yoke and shoe respectively above and below the center of said shoe, the lower one of said springs having 120 its end connected to said yoke above the level of its connection with said shoe, whereby said spring counterbalances part of the weight of said shoe, and both springs tend to withdraw said shoe from said die, in opposition to said lever head; a fulcrum bolt for a bending lever in said frame in coaxial relation with said die face; a bifurcated bending lever having one of its bifurcations fulcrumed on said bolt and hav- 125 130

- ing opposite pintle slots in its bifurcations with their axes parallel with said frame axis, the upper slot being wider than the lower slot, said lever having a radial screw threaded socket in its bight; a pintle extending in said slots with its axis parallel with the axis of said frame, the lower end of said pintle being of reduced diameter to fit the narrower slot; a die roller mounted 5 to rotate on said pintle and having a toric channel in its circumference complementary to the toric channel in said die frame; a U-shaped roller housing fitted to slide between the bifurcations of said lever, parallel therewith, having perforations in its limbs to receive said pintle and having its limbs respectively interposed between said roller and the bifurcations of said lever, and having a cylindrical plunger bearing extending radially in its bight; a housing plunger having a screw thread fitted in the screw thread of said lever, having a wrench hold at its outer end, and having its inner end reduced and mounted to turn in the bearing in said 10 housing bight; a nut on the reduced end of said plunger; and means preventing accidental displacement of said nut; whereby said roller may be adjusted toward and away from said die face, by rotation of said 15 plunger in said bending lever; and a tubular handle, detachably fitted over said plunger; whereby said roller may be caused to traverse said die face to bend a pipe held by said clamping shoe.
- 35 9. In a pipe bending mechanism, the combination with a base; of a die frame having a cylindrically curved face, with its axis extending vertically with respect to said base and with a toric die channel extending circumferentially in said face, adapted to receive substantially one-half of the diameter of the pipe to be bent; a pipe clamping device, including a U-shaped yoke extending substantially radially with respect to said 40 axis, its limbs having respective ribs extending in parallel relation, and radially to said axis; a clamping shoe fitted to slide in said yoke, on said ribs, having a channel complementary to the channel in said frame, and a screw threaded socket extending radially in said shoe toward the bight in said yoke; a screw adjustably fitted in said socket; a clamping lever having an eccentric head extending in said yoke, in opposition to said 45 screw; a fulcrum for said lever, on said yoke; a fulcrum on said base, in coaxial relation with said die face; a bending lever on said base fulcrum; and a die roller, carried by said bending lever, having a toric channel in its circumference complementary to the channel in said die frame.
- 50 10. In a pipe bending mechanism, the combination with a die frame having a curved face and a die channel extending circumferentially in said face; of a pipe clamp- 55 ing device near one end of said die channel; a fulcrum in coaxial relation with said die face; a bifurcated bending lever on said fulcrum, having opposite pintle slots in its bifurcations with their axes parallel with said frame axis, the upper slot being wider than the lower slot and said lever having a radial screw threaded socket in its bight; a pintle extending in said slots with its axis parallel with the axis of said frame; the lower end of said pintle being of reduced diameter to fit the narrower slot; a die roller mounted to rotate on said pintle and having a channel in its circumference complementary to the channel in said die frame; a bifurcated roller housing fitted to slide between the bifurcations of said lever, having axially alined bearings in its bifurcations for said pintle, having its bifurcations respectively interposed between said roller and the bifurcations of said lever, and having a cylindrical plunger bearing extending radially in its bight; and a housing plunger having a screw thread fitted in the socket of said bending lever, and having its inner end mounted to turn in said bearing in said housing; whereby said roller may be adjusted toward and away from said die face, by rotation of said plunger in said bending lever.
- 60 11. In a pipe bending mechanism, the combination with a base; of an arcual series of independently adjustable pedestals on said base; a die frame detachably mounted on said pedestals, and having a curved face, with its axis extending normally with respect to said base, and with a die channel extending circumferentially in said face, adapted to receive the pipe to be bent; a fulcrum on said base, in coaxial relation with said die face; a bending lever on said fulcrum; and a die roller mounted to rotate on said bending lever, having a channel in its circumference, complementary to the channel in said die frame; and means detachably securing said roller on said bending lever; whereby die frames of different sizes may be interchangeably mounted upon said pedestals, and die rollers of correspondingly different sizes, may be interchangeably mounted upon said bending lever.
- 65 12. In a pipe clamping device, a die frame having a channel adapted to receive substantially one-half of the diameter of the pipe to be clamped, and having yoke lugs at respectively opposite edges of said channel; a yoke extending substantially normally to said channel, including a pair of U-shaped plates having perforated ends respectively fitted to said frame lugs, and filling blocks between said plates, in the respective limbs of said yoke; each of said blocks having a rib extending radially with respect to said axis; said ribs extending inwardly with respect to said yoke, and in parallel relation; a clamping shoe fitted to slide in said yoke,

having grooves fitted to said ribs, a channel complementary to the channel in said frame, a screw threaded socket extending radially in said shoe toward the bight in said yoke, a 5 cap screw adjustably fitted in said socket, and a set screw in said shoe arranged to hold said cap screw in adjusted position; a clamping lever having an eccentric head extending between said plates, in opposition to said 10 cap screw; a fulcrum bolt extending through said plates and lever; springs connecting said yoke and shoe respectively above and below the center of said shoe, the lower one of said springs having its ends connected to 15 said yoke above the level of its connection with said shoe, whereby, said spring counterbalances part of the weight of said shoe, and both springs tend to withdraw said shoe from said frame, in opposition to said lever 20 head.

13. In a pipe clamping device, a die frame having a channel adapted to receive substantially one-half of the diameter of the pipe to be clamped, and having yoke lugs at 25 respectively opposite edges of said channel; a yoke extending substantially normally to said channel, having perforated ends respectively fitted to said frame lugs, each limb of said yoke having a rib; said ribs 30 extending inwardly with respect to said yoke, and in parallel relation; a clamping shoe fitted to slide in said yoke, having grooves fitted to said ribs, a channel complementary to the channel in said frame, a screw threaded 35 socket extending radially in said shoe toward the bight in said yoke, a screw adjustably fitted in said socket; a clamping lever having an eccentric head extending in opposition to said screw; a fulcrum bolt extending through said yoke and lever; and 40 springs connecting said yoke and shoe respectively above and below the center of said shoe, the lower one of said springs having its end connected to said yoke above the 45 level of its connection with said shoe, whereby, said spring counterbalances part of the weight of said shoe, and both springs tend to withdraw said shoe from said frame, in opposition to said lever head.

50 14. In a pipe clamping device, a die frame having a channel adapted to receive substantially one-half of the diameter of the pipe to

be clamped, and having yoke lugs at respectively opposite edges of said channel; a yoke extending substantially normally to said 55 channel, having perforated ends respectively fitted to said frame lugs; a clamping shoe fitted to slide in said yoke, having a channel complementary to the channel in said frame, a screw threaded socket extending radially 60 in said shoe toward the bight in said yoke, a screw adjustably fitted in said socket; a clamping lever having an eccentric head in opposition to said screw; a fulcrum bolt extending through said yoke and lever; and a 65 spring connecting said yoke and shoe, tending to withdraw said shoe from said frame, in opposition to said lever head.

15. In a pipe clamping device, a die frame having a channel adapted to receive part of 70 the pipe to be clamped, and having yoke lugs; a yoke having perforated ends respectively fitted to said frame lugs; a clamping shoe fitted to slide in said yoke, having a channel complementary to the channel in 75 said frame, a screw threaded socket extending radially in said shoe toward the bight in said yoke, a screw adjustably fitted in said socket; a clamping lever having an eccentric head in opposition to said screw; and a fulcrum in said yoke.

16. In a pipe clamping device, a die frame having a channel adapted to receive part of the pipe to be clamped; a U-shaped yoke extending substantially normally to said channel; a clamping shoe fitted to slide in said yoke, having a channel complementary to the channel in said frame; a clamping lever having an eccentric head in opposition to said shoe, and a fulcrum on said yoke; an 85 element adjustable between said shoe and lever, arranged to vary the effect of said lever on said shoe; and a spring connecting said yoke and shoe tending to withdraw said 90 shoe from said frame, in opposition to said lever head.

In testimony whereof, I have hereunto signed my name at Philadelphia, Pennsylvania, this nineteenth day of July, 1918.

GEORGE P. McARTHUR.
